FIG. 10

UNITED STATES PATENT OFFICE.

HENRY CURTIS, OF CHICAGO, ILLINOIS.

KNOT-TYING DEVICE FOR GRAIN-BINDERS.

SPECIFICATION forming part of Letters Patent No. 247,748, dated October 4, 1881.

Application filed June 11, 1879.

To all whom it may concern:

Be it known that I, HENRY CURTIS, of Chicago, in the county of Cook and State of Illinois, have invented a certain new and useful 5 Knot-Tying Device for Grain-Binders, of which the following is a full and exact description, reference being had to the accompanying drawings, in which—

Figure 1 is a plan view of the entire device; 10 Fig. 2, an enlarged transverse section at the line xx ; Fig. 3, an end elevation; Fig. 4, a plan view of the knot-tying mechanism; Fig. 5, a plan view of the cutting device; Figs. 6, 7, 8, and 9, enlarged details, showing the different stages 15 in the operation of tying the knot; and Fig. 10, an enlarged detail of the spring-stud b .

My invention consists of the mechanism herein shown and described for constituting a knot-tying device for mechanically tying knots for 20 fastening the cords or ropes used in grain-bind- 25 ers as bands for the sheaves of grain.

As shown in the drawings, A is the bed-piece of the device, provided at one end with the table A', on which the knot-tying mechanism is 25 located.

B is a sliding head or traveler, adapted to slide on the guides B' by any suitable reciprocating mechanism, for the purpose of imparting to the different parts of the tying mechanism 30 their requisite movements, as hereinafter described. Said traveler is provided with the spring-studs b , b' , and b'' , which are so arranged that they will readily yield to a pressure when it is applied to one side of them, but when applied to the opposite side they remain inflexible. It is also provided with a wedge-shaped flange, b^3 , and a projecting arm, b^4 , for the purposes hereinafter set forth.

C is a pinion attached to the sleeve c , which 40 has a partial rotative motion in the bearings c' on the table A'. A lip, c^2 , extends from the front end of said sleeve, and has attached to it a wing or pallet, c^3 , arranged perpendicularly to the axial line of the sleeve to move between the vertical plates a and a' , attached to the table A'.

D is a pin or bolt arranged to slide endwise in the sleeve c , but not partaking of the rotatory motion of the sleeve. Said pin is provided 45 with fluted grooves running lengthwise, into which the cords are pressed and retained against any strain produced by the expansion

of the sheave or by the rubbing action of the lip c^2 . Near the front end of said pin a mortise is cut crosswise and horizontally through it, 55 and at its rear end the lugs d' are fixed to prevent the pin from being rotated by the sleeve c .

E is a sliding rack, gearing into the pinion C to impart a rotatory motion to the sleeve c .

F is a tucker, made in a curved form and having an oscillatory movement in circular ways formed in the table A'. It is so arranged that its contracted point f will enter the mortise d of the sliding pin D. Said tucker is connected by the rod f' to the lever I, from which its motion is derived.

G is a bifurcated arm having one arm, g , arranged above the table A' to move against the face of the vertical plate a , and the other arm, g' , below the table, and extending back of the face-line of the plate a to the edge of the wing c^3 when the arm g lies against the face of the plate a . Said bifurcated arm is pivoted to the table A', and is connected by the rod g^2 to the arm g^3 , pivoted to the bed-piece A, and provided with the retractive spring g^4 and a pendent ear, g^5 , against which the spring-stud b of the traveler B engages when the traveler is moving toward the table A' to force the arm g in contact with the vertical plate a .

H is a spring-detent, pivoted to the table A' to secure the arm g against the plate a . Said detent is provided with a pendent pin, h , against which the wedge-shaped flange b^3 of the traveler strikes to move the detent to release the arm g .

I is a lever, pivoted to the table A', and provided with a pendent flange, i , arranged at an angle to the center line of the lever, as shown in Fig. 1, against which the spring-stud b' of the traveler engages, so as to move said lever and thereby impart to the tucker F its required motion for carrying the point of the tucker into the mortise of the pin D. A spring, i' , connects the lever I to the bed-piece A, to produce a quick return movement of said lever.

J is a lever, pivoted to the bed-piece A and connected at one end to the sliding rack E, for the purpose of imparting to said rack its requisite motion. Said lever has three pendent flanges. The first one, j , being at the free end of the lever, has its major part arranged in a curved line at an angle to the center line

of the lever, as shown in the drawings. The second one, j' , is fixed near the pivotal center of the lever, but beyond the center in respect to the flange j . The third one, j^2 , is located near the end of the second, and is arranged at an angle, as shown, to the center line of the lever. These flanges, by engaging with the spring-stud b of the traveler, produce the requisite movement of the lever J to operate the sliding rack E in the following manner: The parts being in the positions shown in Fig. 1, the traveler B moves forward, carrying the spring-stud b in contact with the flange j , and the stud, striking its inflexible side against the flange, forces the end of the lever to swing back until the stud has passed over the elbow of the flange. When this is accomplished the lever has moved the rack H to the full extent of its movement in one direction. By the continued forward movement of the traveler the spring-stud b is passed behind the flange j' , (the stud yielding for that purpose,) and produces no movement of the lever. The stud b then engages with the flange j^2 , and, during the balance of the forward movement of the traveler, produces a slight retrograde movement of the lever, followed by a slight pause in the movement of the lever at the commencement of the change of direction in the movement of the traveler. On the return movement of the traveler the spring-stud b engages with the face of the flange j' and forces the lever back to its normal position before the stud b has reached a point abreast of the pivotal center of the lever. Passing from the flange j' the stud b glides behind the flange j , and, yielding to the curvature of said flange, produces no movement of the lever J .

K is a rock-shaft, provided with an arm, k , against which the projecting point b^4 of the traveler strikes at the proper time to turn the rock-shaft in its bearings against the resistance of the spring k' . A second arm, k^2 , on the rock-shaft has its point inserted in an opening in the rear end of the pin D , for the purpose of sliding the said pin endwise by the movement of the rock-shaft.

L is an arm, pivoted beneath the bed-piece A , and so arranged in the path of the spring-stud b^2 that on the forward movement of the traveler B the said stud will engage with the said arm and swing it on its pivot; but on the return movement of the traveler the said stud will yield in passing the arm L , which is held by a stop-pin against the pressure of the stud. A rod, M , is attached to the arm L and runs forward, through the guide N , beneath the bed-piece. The end of the rod M engages with an arm, O , pivoted to the bed-piece, and having a retractive spring, o' , attached to it for the purpose of returning the arm to its normal position when relieved from the pressure of the rod M . The arm O is also provided with a supplementary lip-piece, o^2 , adapted to turn on a pivot on said arm, and having a spring, o^3 , arranged to press the heel o^4 of the lip-piece against the stop-pin o^5 .

P is a cutting-wheel, pivoted to a bracket, p , beneath the table A' . Said cutting-wheel is made with radial arms, the sharpened edges of which, as the wheel is turned, come in close contact with the sharp under edge of the bracket, and the two combined form a cutting device for severing the cords. The cutting-wheel P receives its motion from the arm O , which, as it is pressed forward by the rod M , turns the cutting-wheel one-eighth of a revolution. When the arm O is released from the pressure of the rod the spring o' carries it back to its normal position, and in passing the interfering arm of the cutting-wheel the lip-piece o^2 turns upon its pivot, so as to avoid moving the cutting-wheel backward.

Q is a leaf-spring secured beneath the bracket p , and bearing against the under side of the cutting-wheel for the purpose of holding the free end of the cord as it is cut from the cord on the reel for each length required for a band. Said spring is provided with a notch, q , which lies directly under the opening between the pin D and lip c^2 , so that the cord will lead fairly into said opening. The notch q also prevents the cord from slipping away from the action of the cutting-wheel.

The operation of my device is as follows: The different parts of the device being in the positions shown in Fig. 1, and the end of the cord caught between the cutting-wheel P and spring Q , the cord is drawn up by the binding-arm of my grain-binder, (shown and described in the specification which I have heretofore filed at the Patent Office.) In effecting this the standing part of the cord is drawn through the slot a^2 in the table A' and into the opening between the lip c^2 and the side of the pin D , which is cut away for the purpose of facilitating the entry of the cord. The grain to be bound is pressed back by the action of the binder-arm against the standing part of the cord, and then by the descent of the binding-arm the cord is carried around the bundle of grain and beneath the cutting-wheel, where it engages in the notch q of the spring Q . The traveler B then moves forward toward the table A' , and its spring-stud b , by striking the pendent ear g^5 of the arm g^2 , moves said arm to close the arm g against the face-plate a , where it is locked by the detent H . By this action of the arm g both parts of the cord are entered between the lip c^2 and pin D . The movement of the traveler next brings the spring-stud b^2 against the arm L , which through the mechanism hereinbefore described turns the cutting-wheel P to sever the two parts of the cord. The continued movement of the traveler next brings the spring-stud b against the pendent flange j of the lever J , moving the said lever, and through the intermediate mechanism hereinbefore described the lip c^2 of the sleeve of the pinion C , whereby the two ends of the cord are carried around the pin D , as shown in Fig. 7. Then the spring-stud b^2 engages with the lever I , as hereinbefore described, and causes the tucker F to force the two ends of the cord through the

135

mortise d of the pin D, as shown in Fig. 8. The wedge-shaped flange b^3 of the traveler moves the detent to release the arm g, and then the projecting point b^4 of the traveler strikes the 5 arm k and turns the rock-shaft K to draw back the pin D, as shown in Fig. 9. The ends of the cord, being in the mortise d , are by this movement carried through the loops that were formed around the pin D. By the expansion of 10 the bundle of grain the loops are drawn snugly around the ends of the cord so as to form a close knot. As the traveler moves back on its return movement the spring k' forces back the rock-shaft K and returns the pin D to its normal position, so as to release the ends of the 15 cords, and freeing the tied bundle, so that it may be discharged from the machine. The return of the traveler to the positions shown in Fig. 1 restores all the parts to their positions for a 20 repetition of the operation described.

By grooving the pin D, as herein described, provision is made for retaining a firm hold of the cord against the strains thrown upon it by the expansive force of the bundle of grain, and 25 against the rubbing action of the lip c^2 and wing c^3 , by which the cord is pressed into the grooves without producing any damage to it. When desired, the tucker F may be made straight and arranged to slide in straight 30 guides fixed perpendicular to the center line of the pin D; but I preferably curve it, as herein shown and described.

I claim as my invention—

1. A knot-tying device consisting of a lip, c^2 , adapted to partially rotate around a pin on 35 which the loops of the cord are formed, a reciprocating pin, D, provided with a mortise, d , and a tucker, F, all substantially as and for the purpose specified.

2. The combination, with the traveler B, provided with the spring-stud b , of the arms G and g^3 , rod g^2 , and detent H, substantially as and for the purpose specified. 40

3. The table A', provided with the vertical plate a and slot a^2 , in combination with the 45 arm G, lip c^2 , and reciprocating pin D, as and for the purpose specified.

4. The combination, with the traveler B, provided with the spring-stud b , of the lever J, 50 rack E, and pinion C, provided with the sleeve c and lip c^2 , as and for the purpose specified.

5. The combination, with the traveler B, provided with the spring-stud b' , of the lever I and tucker F, as and for the purpose specified.

6. The combination, with the traveler B, provided with the spring-stud b^2 , of the arm L, connected by the rod M, to operate the arm O, 55 provided with the supplementary lip o^2 , and the cutting-wheel P, as and for the purpose specified.

HENRY CURTIS.
